[57] CLAIM

The ornamental design for a register faceplate, as shown and described.

DESCRIPTION

FIG. 1 is a perspective view of a register faceplate, showing our new design;

FIG. 2 is a top plan view;

FIG. 3 is a front elevation view, the rear elevation view being a mirror image thereof;

FIG. 4 is a right side elevation view, the left side elevation view being a mirror image thereof;

FIG. 5 is a perspective view of a second embodiment of the register faceplate of FIG. 1;

FIG. 6 is a top plan view of the embodiment of FIG. 5; and, FIG. 7 is a right side elevational view of the embodiment of FIG. 5.
